UNITED STATES PATENT OFFICE.

JOSEPH N. MAHONEY, OF WILKINSBURG, PENNSYLVANIA, ASSIGNOR TO WESTINGHOUSE ELECTRIC & MANUFACTURING COMPANY, A CORPORATION OF PENNSYLVANIA.

CIRCUIT INTERRUPTER.

Application filed December 8, 1917. Serial No. 206,131.

To all whom it may concern:

Be it known that I, JOSEPH N. MAHONEY, a citizen of the United States, and a resident of Wilkinsburg, in the county of Allegheny and State of Pennsylvania, have invented 5 a new and useful Improvement in Circuit Interrupters, of which the following is a specification.

My invention relates to circuit interrupters and particularly to circuit interrupters of the quick-acting type.

One object of my invention is to provide a circuit interrupter that shall require a minimum movement of its operating mechanism to completely open the same, have its accelerating spring exert its maximum effectiveness at the instant of separation of the contact members and require a minimum time interval between the energization of 20 its tripping electromagnet and the buckling or upsetting of its toggle mechanism.

Another object of my invention is to provide an interrupter of the above indicated character that shall have contact members 25 of such shape that any arc, which may be drawn when the circuit is interrupted, shall be extinguished within a minimum interval of time.

A further object of my invention is to 30 provide a circuit interrupter of the above indicated character that shall be simple and inexpensive to construct and effective in its operation.

In practicing my invention, I provide two 35 stationary main contact members, two stationary arcng contact members of substantially horn shape, a slidable rod having bridging contact members at the upper end thereof and a toggle mechanism connected 40 between the lower end of the rod and a stationary member. A tripping electromagnet is provided for actuating a member that is adapted to limit the oversetting of the toggle mechanism and to directly move such 45 mechanism over its dead-center position to trip the interrupter within a minimum period of time. A spring serves to move the rod downwardly and is adapted to exert its maximum accelerating force at the instant 50 the toggle is moved over its dead-center position. A removable handle is provided for setting or closing the interrupter and a magnetic blow-out coil may be provided for extinguishing any arcs that may be drawn 55 when the interrupter is tripped.

Figure 1 of the accompanying drawings is a front elevational view of a circuit interrupter embodying my invention, and Fig. 2 is a side elevational view of a portion of the circuit interrupter shown in Fig. 1. 60

A circuit interrupter 1 is connected in series with the conductors 2 of an electric circuit and is adapted to quickly operate under predetermined overload conditions in the 65 circuit.

The circuit interrupter 1 comprises, in general, a supporting member or frame 3, stationary main contact members 4, auxiliary stationary arcng contact members 5, a slideable rod 6 having a main bridging contact 70 member 7 and an auxiliary bridging contact member 8 mounted at the upper end thereof and a toggle mechanism 9 disposed between the lower end of the rod 6 and a stationary pin 10. An electromagnet 11 is 75 adapted to be energized, through a condenser 12, from the circuit to be protected, under predetermined conditions, for the purpose of directly upsetting the toggle mechanism to thereby trip the interrupter 1. A 80 removable operating handle 13 is provided for actuating or setting the toggle mechanism 9 to close the interrupter.

The stationary main contact members 4 are preferably of the spring-leaf construction to permit effective engagement with the bridging contact member 7 when the toggle mechanism 9 is slightly overset. The auxiliary contact members 5 are of substantially horn shape to permit the arc, that is drawn 90 when the interrupter is opened, to be extinguished. The outer surfaces 14 of the members 5 are formed of relatively high-resistance conducting material, and barrier members 15 are disposed in fan-wise relation between the members to break the arc into a 95 number of component parts. The members 15 are formed of relatively high-resistance material, such as carborundum, in order to effectively extinguish the arc. A magnetic 100 blowout coil 16 is connected in circuit with conductors 2 and is adapted to co-operate with an arc chute (not shown) and pole pieces 16a to so deflect the arc between the members 5 as to effectively extinguish the 105 same.

The rod 6 is guided by bearing members 17 and is provided with an insulating member 18 to effectively insulate its upper portion 19 from its lower portion 20. A spring 110

21 is disposed between the bearing members 17 and the enlarged lower end 20 of the rod 6 for the purpose of exerting a downward force on the rod. The toggle mechanism 9 5 comprises two links 22 and 23 that are connected between the lower end 20 of the rod 6 and the pin 10 in a bracket 24 on the frame or supporting member 3. A pin 25 is supported in the bracket 24 and is adapted to 10 receive a hooked portion 26 of the operating handle 13. The inner end of the handle 13 is adapted to engage the knee portion 27 of the toggle mechanism 9 for the purpose of forcing the same across its dead-center position to compress the spring 21 and effect the 15 engagement of the contact members 4 and 7 and the members 5 and 8.

The tripping magnet 11 is mounted on the frame 3 and comprises a stationary laminated 20 magnetizable core 28, a winding 29 and a movable laminated core member or armature 30. The core 28 of the electromagnet 11 is constructed of laminated material for the purpose of obtaining a maximum rate of 25 change of magnetic flux and rendering the magnet capable of accelerating the movement of its armature in a relatively short period of time. A member 31 of substantially L-shape is mounted on the pin 10 and 30 its arm 32 is operatively connected to the armature 30 of the electromagnet 11. The arm 33 of the member 31 is adapted to engage an adjusting screw 34 that is mounted on the bracket 24 and thereby limit the oversetting of the toggle mechanism 9 to a relatively small amount.

When a short circuit obtains between the conductor 2 and ground, the voltage across the condenser 12 and the winding 29 of the 40 tripping electromagnet 11 will change suddenly to cause the condenser 12 to discharge. This will energize the winding 29 and cause the armature 30 to quickly move upwardly to actuate the member 31. Since the arm 33 45 of the member 31 limits the oversetting of the toggle mechanism 9, a slight movement of the same will move the toggle mechanism 9 over its dead-center position to permit the spring 21 to exert its maximum accelerating 50 force in effecting a downward movement of the contact member 7. After the contact members 4 and 7 are disengaged, the bridging member 8 will be disengaged from the arcing contact members 5, and any arc that 55 may be drawn will be deflected by the blow-out coil 16 and be so broken up and limited in value by the barrier members 15 that it will be effectively extinguished.

It will be understood that the tripping

electromagnet 11 is adapted to operate directly on the toggle mechanism to upset the same and that the spring 21 is adapted to exert its maximum force to disengage the contact members. By this arrangement, maximum speed of operation of the interrupter is obtained, and, when the electromagnet is energized by a condenser that is responsive to relatively quick voltage changes in the circuit, it functions to effect interruption of the circuit substantially in anticipation of the actual over-loads on the same.

My invention is not limited to the particular structure illustrated, as various modifications may be made therein without departing from the spirit and scope of the invention as set forth in the appended claims.

I claim as my invention:

1. In a circuit interrupter, the combination with a contact-carrying rod, means for biasing the rod longitudinally and a toggle mechanism connected between one end of the rod and a stationary member, of a lever for upsetting the toggle mechanism having an adjustable stop portion for engagement with said mechanism in the overset position thereof.

2. In a circuit interrupter, the combination with a contact-carrying rod, means for biasing the rod longitudinally and a toggle mechanism connected between one end of the rod and a stationary member, of a lever for upsetting the toggle mechanism, having a stop portion engaging said mechanism in the overset position thereof, and adjustable means engaging said stop portion for adjusting the amount by which said mechanism is overset.

3. A circuit interrupter comprising a contact-carrying rod, means for biasing the rod longitudinally, a toggle mechanism connected to one end of the rod, an electromagnet provided with a movable core member for upsetting the toggle mechanism, and a single means for adjusting both the toggle mechanism in its overset position and the position of the said core member with respect to the electromagnet.

4. In a circuit interrupter provided with a toggle-actuating mechanism, a removable handle member having a hook portion for pivoted connection to a stationary member and a portion for engagement with the said toggle mechanism to actuate the same.

In testimony whereof, I have hereunto 115 subscribed my name this 28th day of Nov. 1917.

JOSEPH N. MAHONEY.
